UNITED STATES PATENT OFFICE.

WILLIAM R. HURD, 2d, OF BEVERLY, MASSACHUSETTS, ASSIGNOR TO UNITED SHOE MACHINERY CORPORATION, OF PATERSON, NEW JERSEY, A CORPORATION OF NEW JERSEY.

MANUFACTURE OF TOOLS.

Original application filed March 11, 1918, Serial No. 221,812. Divided and this application filed July 29, 1920. Serial No. 399,785.

To all whom it may concern:

Be it known that I, WILLIAM R. HURD, 2d, a citizen of the United States, residing at Beverly, in the county of Essex and State of Massachusetts, have invented certain Improvements in the Manufacture of Tools, of which the following description, in connection with the accompanying drawings, is a specification, like reference characters on the drawings indicating like parts in the several figures.

This invention relates to the marking of tools and particularly steel tools on or in which marks of identification or other significance are impressed. In some cases, for example rotary cutters used for trimming the edges of shoe-soles, the most convenient if not the only practical location for such marks is on or in one of the flat end faces 20 that lie at right angles to the axis. Nearly all if not quite all cutters for the purpose mentioned have hubs at their rear ends and it has been common if not universal practice to apply identification marks such as the 25 name or initials of the manufacturer, a trademark, or numerals denoting the size, style or other distinguishing features by impressing them into the rear face of the hub. This location has disadvantages both from the 30 standpoint of the manufacturer and also from that of the user, and in order to show just how these disadvantages arise it will be well to consider the necessary steps in the manufacture of the tools as heretofore practiced.

After a cutter blank has been turned, bored, milled, and otherwise machined to the desired form, but before it is hardened, impression dies are brought to bear against the 40 end of its hub to provide it with the necessary marking while the metal is sufficiently soft to receive the impressions. After the impressions have been made the cutter is hardened and then ground to sharpen it and 45 to true its front face so as to provide a flat seat for the rand-crease guard or shield. The rear end of the hub has been chosen for receiving such impressions because it does not require grinding and therefore the legibility of the impressions is unimpaired, but, 50 for reasons hereinafter stated, the radial thickness of the hubs is so much restricted

that the impressing operation distorts the bore and reduces its diameter. In order, therefore, to make the cutter fit the shaft or 55 holder on which it is to be mounted for use, and also so that it will run true, it has been necessary to ream the bore after the marks have been impressed.

This invention provides a new method of 60 manufacture by which the aforesaid objections are avoided and by which a new and improved cutter is produced, the present application being a division of my former application Serial No. 221,812, filed March 11, 65 1918.

Although, for convenience, the present invention is described particularly with regard to cutters for trimming the edges of shoe-soles its fundamental principles and advantages are applicable to any steel tool that requires hardening and grinding and in which 70 it is necessary or desirable to impress identification marks.

In one respect, therefore, the invention 75 consists in forming a depression in a face that for any reason will subsequently require grinding, and in impressing the marks on or in the surface forming the depression so that they will be below the plane of the 80 ground surface and therefore will not be obliterated by the grinding operation.

In the case of cutters for the purpose stated the front face of each cutter must be flat and lie truly at right angles to the axis 85 so as to provide a suitable seat for the usual shield by which the cutter is prevented from scarring the upper of the shoe. Accordingly, a feature of the present invention consists in forming a depression, preferably an 90 annular, concentric depression, in the front face of the cutter and thereafter impressing the marks on or in the surface of this depression so far from the bore that the latter 95 will not be distorted. This not only affords a relatively large area for the impressions but avoids the necessity of the reaming operation hereinbefore mentioned.

Another feature of the invention consists 100 in forming the depression so that the shield will cover and close it and thus prevent dust and dirt from accumulating in the depression sufficiently to obscure the identification marks.

The several features of the invention are illustrated by the accompanying drawings and are hereinafter described and claimed.

Referring to the drawings,

5 Fig. 1 represents a perspective view of a rotary edge-trimming cutter embodying the invention;

10 Fig. 2 represents such a cutter in section as being held in the jaws of a rotary holder by which it is rotated in contact with the grinder in contact with its front face; and

15 Fig. 3 is a section including a portion of an edge-trimming machine including such a cutter assembled with other elements of well-known construction in such machines.

According to the example illustrated the cutter comprises a body portion 10; a hub 11 extending to the rear, and teeth 12 having cutting edges. Before the cutter blank has 20 been hardened or ground a depression 13 is formed in the front face of the body portion, said depression preferably being formed by turning so as to preserve accurate balance. The depression is preferably formed so as to leave a concentric annular flange 14 contiguous to the bore for sustaining the shield against the pressure of its attaching screw, and furthermore it is preferably formed so as not to intersect the notches between the 25 teeth 12. This leaves a continuous annular shoulder or surface 15 against which the shield may be seated to prevent dust and dirt from working into the depression from the notches between the teeth 12. After this 30 depression is formed and before the blank has been hardened any desired words, numerals, or other symbols may be impressed into the body 10 in the surface forming the depression. Fig. 1 includes two groups of 35 symbols indicated at 16, 17. These symbols need not be impressed deeply because they lie below the plane to which the front face of the cutter will subsequently be ground.

40 After the impressions have been made the blank may be hardened and then presented to a grinder such as that indicated at 18 in Fig. 2. As shown by this figure the cutter is clamped by jaws 19, 19 forming parts of a rotary holder 20, the formations of the 45 cutter and jaws being such as to maintain the axis of the cutter in concentric relation to that of the holder. The grinder 18 is carried by a rotary shaft 21 which is driven while the holder 20 is also driven, the front 50 face of the cutter being thereby ground and trued to a plane at right angles to the axis of the cutter. The flange 14, shoulder 15, and teeth 12 are thus ground to a common 55 plane forming a seat for the shield 22 illustrated in Fig. 3.

60 Fig. 3 represents a fragment of an edge-trimming machine of well-known construction and includes a cutter-shaft 23, a bearing 24 therefor, an expansible thimble 25, the 65 shield 22, and a screw 26 for holding the

parts in assembled relation. The shaft has a tapering portion 27 to which the thimble 25 is fitted. This thimble fits the bore of the cutter and is provided with a flange 28 arranged to abut against the rear end of the 70 hub of the cutter. The shield 22 has a flat face that lies against the ground and trued front face of the cutter and that covers the depression 13 so as to exclude dirt. The shaft is bored and tapped to receive the 75 screw 26 and when the latter is tightened it not only clamps the shield against the front face of the cutter but forces the thimble along the tapering portion of the shaft so that the thimble is expanded to form a tight 80 coupling between the shaft and the cutter.

It has been stated that the hub of the cutter is restricted to a relatively small radial dimension. This condition is due in part, at least, to the common practice of 85 using some kind of a supplementary tool or device with the cutter. In some cases a feather-edging device is mounted on the hub of the cutter while in other cases a heel-breast-guard in the form of a ring is mounted on the hub in place of the feather-edger. Fig. 3 includes broken lines representing conventionally a feather edger 30 of well-known construction, such device comprising 90 operating blades interposed between the 95 teeth of the cutter and a hub or body portion 31 bearing on the hub of the cutter. These are sufficient examples of the reason why the radial dimension of the hub of the cutter is so much restricted that the identification marks may not be impressed legibly into the hub without being so close to the bore as to produce the aforesaid distortion and require the aforesaid reaming to correct the distortion. 100

Having thus described my invention, what I claim as new and desire to secure by Letters Patent of the United States is:

1. That improvement in the art of manufacturing cutters which consists in forming 110 a depression in the end of the cutter, stamping commercial data in the depression, hardening the cutter and grinding the end face.

2. That improvement in the art of manufacturing cutters which consists in forming 115 an annular depression in the end of the cutter, leaving a rib at the bore to support a guard, stamping commercial data in the depression, hardening the cutter and grinding the end face. 120

3. That improvement in the art of manufacturing rotary sole-trimming cutters, which consists in forming a depression in the front face of a cutter, impressing one or more marks on or in the face forming said depression, hardening the cutter, and grinding the front face so as to true it but not so deeply as to touch the impression-bearing face of said depression. 125

4. That improvement in the art of manu- 130

facturing rotary sole-trimming cutters having hubs of relatively small radial dimension projecting from the rear face of the body portions, which consists in forming a depression in the front face of the body portion so that a portion of said depression will be farther from the center than the rim of the rear end of the hub is, impressing one or more marks in the face forming said depression so that some portion of said mark or marks will be farther from the center than said rim is, hardening the cutter, and grinding the front face of the body portion so as to true it but not so deeply as to touch the impression-bearing face of said depression.

5. That improvement in the art of manufacturing rotary cutters, which consists in

turning a concentric depression in a transverse face of a cutter-blank, impressing one or more marks in said depression while the blank is relatively soft, and thereafter hardening the blank and grinding said face so as not to obliterate said mark or marks.

6. That improvement in methods of marking machine parts which consists in making a depression in a bearing surface of a steel part while the steel is soft, impressing one or more marks in the bottom of said depression, hardening the part, and grinding said bearing surface to true it.

In testimony whereof I have signed my name to this specification.

WILLIAM R. HURD, 2ND.
